Des. 210,746
Patented Apr. 9, 1968

210,746

AIR CLEANER TESTER

Toyoo Yamada, 7-14 Chuo 5-chome, Ohta-ku,
Tokyo, Japan

Filed July 28, 1966, Ser. No. 3,238

Term of patent 14 years

(Cl. D52—6)

FIG. 1

FIG. 2

FIG. 3

FIG. 4

FIG. 5

FIG. 6

FIG. 1 is a front elevational view of an air cleaner tester, showing my new design;

FIG. 2 is a rear elevational view;

FIG. 3 is a bottom plan view;

FIG. 4 is a top plan view;

FIG. 5 is a side elevational view thereof; and

FIG. 6 is a perspective view of the tester, such view being taken at a position 180° removed from the view of FIG. 5.

I claim:

The ornamental design for an air cleaner tester, as shown.
